UNITED STATES PATENT OFFICE.

CHARLES W. CRAMER AND HARRY C. HAAK, OF SCRANTON,
PENNSYLVANIA.

WASHING-MACHINE.

SPECIFICATION forming part of Letters Patent No. 759,678, dated May 10, 1904.

Application filed February 13, 1903. Serial No. 143,247. (No model.)

To all whom it may concern:

Be it known that we, CHARLES W. CRAMER and HARRY C. HAAK, citizens of the United States, residing at Scranton, in the county of 5 Lackawanna and State of Pennsylvania, have invented certain new and useful Improvements in Washing-Machines; and we do hereby declare the following to be a full, clear, and exact description of the invention, such as will 10 enable others skilled in the art to which it appertains to make and use the same.

Our invention relates to improvements in washing-machines, and particularly to that 15 class of machines which are provided with means whereby hydraulic, pneumatic, or other pressures may be employed for operating the machine.

The invention consists in certain novel constructions, combinations, and arrangements of 20 parts, as will be hereinafter fully described and claimed.

In the accompanying drawings, Figure 1 is a vertical central section through a washing-machine embodying our invention. Fig. 2 is 25 a plan view of a part of the tub, showing the float within the same and the bottom of the tub. Fig. 3 is a detail cross-sectional view through the central post of the washing-machine. Fig. 4 is a detail view illustrating the latch employed for preventing the said post from 30 becoming loosened during the operation of the machine. Fig. 5 is a detail perspective view showing the locking means for holding the tub stationary. Fig. 6 is a detail vertical sectional 35 view through a portion of the washing-machine, showing a different means for connecting the pressure-cylinder with the tub.

The washing-machine which is the subject of the present invention is adapted to be moved 40 upon a pivot-pin back and forth, first in one direction and then in the other, the movements in the opposite direction being taken in quick succession, so as to cause a rubbing action between the clothing or other articles placed in the 45 tub and the inner surfaces of the tub, the bottom, and the float arranged therein. The tub is also so mounted that it may be connected with a pressure-cylinder so as to be rotated back and

forth automatically by power. In carrying out these features of the invention we form 50 the machine with a main receptacle or tub 1, which is pivotally mounted upon a suitable support or base, as 2. The tub is provided with a removable pivot-pin, as 3, which projects downwardly through an elongated bearing 4, which is secured to the top of the base 2. The bearing 4 is preferably formed integral 55 with a casting 5, which surrounds the upper ends of the legs 6 6 thereof. The upper end of the pivot-pin 3 is screw-threaded and engages threads in a boss 7, formed on the spider 8, which is secured to the under side of the tub-bottom, the said screw-threaded portion of the said pivot-pin also extending through the bottom of the tub and engaging a central post 9, 60 arranged within the tub. The lower end of the boss 7 is formed with a bearing-surface adapted to engage a bearing, preferably a ball-bearing, as 10, arranged in an annular recess 11, formed in the central portion of the casting 5. The 65 recess 11 is provided with a suitable bearing-lining upon which the balls of the bearing run. The tub will thus rest upon the base 2 on the antifriction ball-bearing thus formed.

Interiorly of the hub and on the bottom 75 thereof is centrally arranged a disk or raised portion 12, the said raised portion being provided with a recess, as 13, in which is secured a plate or disk 14, which is secured to the bottom of the tub surrounding the pivot-pin. 80 The plate 14 surrounds the screw-threaded end of the pivot-pin 3, upon which it is screwed, and is formed at its center and on its upper face with a series of upwardly-extending ratchet-teeth, as 15, which are adapted to be 85 engaged by a latch 16, carried by the post 9. The lower end of the latch is so shaped as to engage the teeth of the said ratchet when the post 9 is screwed down upon the upper end of the pivot-pin 3 and will prevent the said post 90 from being unscrewed from its position when the tub is being used. The latch 16 is preferably clamped in its lowered position by means of a clamp-screw 17, which passes through a slot 18, formed in the shank of the 95 latch 16. The said latch 16 is preferably ar-

ranged in a vertical groove or kerf, as 19, formed in the side of the post 9. A metallic cap or ferrule 20 preferably incloses the lower end of the post 9 and is provided with a 5 threaded aperture to engage the threads on the end of the pivot-pin 3. A movable float or plate 21 is arranged upon the post 9, being movably connected therewith, so that it will rest by gravity upon the clothing or other articles to be washed in the tub. In order to prevent this float from having a movement independent of the post 9, it is provided with a collar 22, which surrounds the post 9 and is formed with an inwardly-extending rib or key 15 23, which extends into the kerf 19 of the said post, so that the float will be turned in correspondence with the movement of the tub and post or will be free to slip up and down on the said post. A cover 24 is placed upon the top 20 of the tub, so as to completely close the upper end thereof. The inner peripheral surface of the tub is formed with a series of corrugations 25, preferably vertically arranged, while the upper surface of the bottom is formed 25 with radially-extending ribs or slats, as at 26. The under side of the float 21 is also provided with radially-arranged ribs or slats, as at 28, for engaging the materials in the tub, and the said float is further provided with a series of 30 apertures 29, so that liquids may pass through the same from one side of the float to the other. The bottom of the tub is preferably provided with a drain-opening or outlet-aperture, as 30, which is controlled by a plug, as 31. The 35 opening is made flaring in shape and the plug formed to fit it. The plug 31 is provided with a stem 32, which extends downwardly through the opening 30 and is bent to one side to form a hook 33. When the plug is lifted, the hook 40 may be brought into engagement with a hook 34 on the bottom of the tub, so as to hold the said plug in its raised position for draining the tub. The pivot-pin 3 is held in its bearing by a suitable nut, as 35, applied to the 45 lower end of the said pin, but not screwed up against the end of the bearing, so as to prevent the free movement of the pin in rotation.

The tub may be locked in a stationary position when desired by means of a latch-lever, 50 as 63, which is pivoted to the base 2 and is adapted to engage at its upper end a pair of lugs 64, secured to the spider 8 or the bottom of the tub. The lower end of the latch-lever 63 extends downwardly a suitable distance and is provided with means for engaging the rack or notched plate 65, secured to the said base. The lever may be moved along 55 this rack, so that it will be brought into or out of engagement with the lugs 64 on the bottom of the tub.

In operating the tub the materials to be washed are placed in the body of the tub upon the bottom. Water and other washing materials may then be placed in the tub, after

which the float 21 is put in position on the 65 post 9, so that it will rest upon the top of the clothes or other materials in the tub. The cover is then put in position, and the tub may be then unlocked by releasing the lugs 64 from the latch-lever 63. The tub is then 70 turned by any suitable means back and forth upon its pivot. The clothing or other materials in the tub will gain momentum in the direction of the movement of the tub, and when the tub is stopped at the end of one motion 75 the momentum will tend to carry the clothes farther around in the tub, especially as the tub is immediately started on its reverse movement. It will thus occur that at each end of the stroke of the tub the clothes will be more 80 or less rubbed between the float and bottom and against the sides of the tub. The tub, float, and bottom, as well as the post 9, are all preferably formed of wood, so that there need be practically no metal contact with the clothing or other materials washed. After the washing operation has been completed the tub may again be locked in a stationary position by means of the latch-lever 63, and the liquids in the tub can be discharged through the opening 90 30.

Having now fully described our invention, what we claim as new, and desire to secure by Letters Patent, is—

1. A washing-machine comprising a tub, 95 means for pivotally supporting the same comprising a stand having a bearing formed therein, a pivot-pin passing upwardly through the bearing and through the bottom of the tub, and adjustable means within the tub for preventing the pivot-pin from dropping out of its bearing, substantially as described.

2. A washing-machine comprising a tub, a standard supporting the same, a bearing formed in the standard, a pivot-pin passing 105 upwardly through the bearing and projecting into the tub through the bottom thereof, an adjustable post in the tub, the said post being provided with means for engaging the pin and adjustable means for locking the post 110 against removal when the machine is in operation, substantially as described.

3. A washing-machine comprising a tub, a standard for pivotally supporting the same, a pivot-pin projecting upwardly through the 115 standard and through the bottom of the tub, a post provided with a screw-threaded socket for engaging the end of the pin which projects into the tub, and adjusting means within the tub for preventing the post from becoming 120 unscrewed from said pin, substantially as described.

4. A washing-machine, comprising a pivotally-mounted tub, a pivot-pin projecting through the bottom thereof, a support holding 125 said pin in position and carrying the tub, a reinforcing-disk secured to the inside of the tub-bottom and surrounding the said pin, a ratchet

secured to said disk, a post engaging the inner end of the pin, a sliding pawl carried by said post and engaging said ratchet for preventing the post from being disconnected from the pin, 5 substantially as described.

5. A washing-machine, comprising a tub pivoted on a suitable base, means for moving the tub back and forth on its pivot-point, a post mounted in the tub, a float vertically movable on the said post but adapted to be rotated therewith, and means for holding the post in position so as to turn with the tub, the inner surface of the tub sides and the inner surfaces of the bottom and float being ribbed 15 for properly engaging clothing or other material to be washed, substantially as described.

6. A washing-machine, comprising a tub or receptacle, and a supporting-base, an elongated central bearing in said base, a pivot-pin 20 provided with screw-threads at its upper end and engaging the said bearing, a spider on the under side of the tub engaging said screw-threads upon the upper end of the said pivot-pin, a post in the tub also screwed on the upper end of the said pivot-pin, a ratchet-plate on the bottom of the tub, a latch carried by the said post and engaging said ratchet-plate, and means for moving the tub back and forth on its pivot, substantially as described.

30 7. A washing-machine comprising a tub, a standard for supporting the tub, a boss projecting from the bottom of the tub and forming a bearing member, a corresponding bearing carried by the standard and supporting 35 said boss and thereby the weight of the tub, a pivot-pin extending upwardly through the standard-bearing and boss and projecting into the tub, and removable means within the tub for supporting the pin against dropping out

of place the pin insuring the holding of the 40 tub properly in position upon its bearing, substantially as described.

8. A washing-machine comprising a tub, a supporting-standard having a central aperture, a bearing at the upper end of said aperture, a boss upon the bottom of the tub engaging said bearing and supporting the tub thereon, a pin for holding the parts in place extending loosely through the apertured standard to the bottom of the tub, a post in 50 the tub for supporting the pin, and a grooved latch carried by the post for preventing it from being disengaged from the pin when the machine is in operation.

9. A washing-machine comprising a tub a 55 standard supporting the same, a bearing interposed between the tub and the standard for allowing the tub to have a pivotal movement on the standard, a pin projecting upwardly through the standard and the bottom of the 60 tub and screw-threaded at its upper end, a post mounted in the tub and engaging the threads of the pin, a float carried by the post and held against movement on said post, and means carried by the post and engaging the 65 bottom of the tub for preventing the post from turning in one direction with respect to the tub while the screw-threads upon the pin prevent the post from turning in the other direction with respect to the tub, substantially 70 as described.

In testimony whereof we hereunto affix our signatures in presence of two witnesses.
